UNITED STATES PATENT OFFICE.

TUDOR T. HALL, OF NEW ORLEANS, LOUISIANA.

GARMENT-STRETCHER.

No. 830,429.

Specification of Letters Patent.

Patented Sept. 4, 1906.

Application filed August 16, 1905. Serial No. 274,461.

To all whom it may concern:

Be it known that I, TUDOR T. HALL, a citizen of the United States, residing at New Orleans, in the parish of Orleans and State of Louisiana, have invented new and useful Improvements in Garment-Stretchers, of which the following is a specification.

The invention relates to an improvement in garment-stretchers, and particularly to a device adapted in use for stretching trousers.

The main object of the invention is the production of a trousers-stretcher arranged to clamp and support the trousers and adapted to apply a uniform and yielding pressure to distend or stretch the garment.

Another object of the invention is the production of tension means for the stretcher, constructed and arranged to be readily and conveniently adjustable to any degree intermediate its extremes, whereby the stretching tension may be varied to suit the requirements of the particular garment.

Another object of the invention is the production of means whereby one of the clamping members is adapted for independent movement relative to the other clamping member, whereby the tension of the stretcher will be equally applied to the garment without particular regard to the proper set of the latter in the stretcher.

The preferred details of construction of the present invention will be specifically described in the following specification, reference being had particularly to the accompanying drawings, wherein—

Figure 1 is a perspective view illustrating a trousers-stretcher constructed in accordance with my invention. Fig. 2 is a vertical central section of the same centrally broken out, and Fig. 3 is a broken rear elevation of the upper clamping member.

Referring to the drawings, it will be noted that my improved trousers-stretcher comprises, essentially, three distinct parts—an upper clamping member, adapted to receive the lower end of the trousers, a lower clamping member, adapted to receive the upper or waist portion of the trousers, and a brace member, movably connecting the clamping members and arranged to maintain said clamping members separated under a yielding tension.

The upper clamping member comprises two plates, hereinafter termed the "base-plate" 1 and "face-plate" 2. The base-plate is of relatively greater thickness and

length than the face-plate to provide desired rigidity of structure at this point. The surface of the base-plate next the face-plate is formed with a curved depression 3, arranged transversely of its length and so positioned as to receive and accommodate the longitudinal or side seam of the trousers-legs when the trousers are in position, and the inner surface of the face-plate is reduced or cut away at 4 to accommodate the extra thickness of material incident to the use of wear or binding tapes at the inner bottom edge of the trousers-legs.

The upper edge of the base-plate is provided with forwardly-projecting lips 5, designed to be engaged by eyes or loops 6, secured in the upper edge of the face-plate, whereby to provide for convenient assembling of the parts in proper relative positions and to guard against independent movement of the face-plate except in a direction at right angles to the plane of the base-plate, as will be obvious. The clamping pressure between the plates 1 and 2 is secured through the medium of clamping-arms 7, provided in duplicate and arranged at the respective ends of the plates. Each arm, preferably of spring metal of the desired strength, is practically of U shape, having one terminal secured to the rear or outer side of the base-plate, the other or free terminal of the arm being of a length and so arranged as to bear upon the outer surface of the face-plate when the parts are assembled. The clamping-arms are pivotally secured to the base-plate and are adapted to be swung to a position to arrange the clamps longitudinally of the plates 1 and 2 or at right angles thereto, being limited in these movements by stops 8, properly positioned on the outer side of the base-plate adjacent the pivot of the arms.

In the first position of the clamping-arms the free terminals thereof bear with the desired spring-pressure upon the outer surface of the face-plate, clamping the latter securely to the base-plate, while in the second position the arms are turned to remove their free terminals entirely out of contact with the face-plate and permit the separation of the latter from the base-plate. A block 9 is pivotally secured to the outer surface of the base-plate and approximately centrally of the length thereof and when in operative position depends below the upper clamping member to provide for the reception of the brace member, as hereinafter described. The pivotal or swiveled connection of the

block with the upper clamping member is an important and material feature of the present invention in that it provides for the application of proper tension to the trousers without regard to their exact and particular position in the stretcher. A supporting hook 10 is preferably secured in the upper end of the block to provide a medium for supporting the stretcher as a whole.

- 10 The lower clamping member comprises a base-plate 11, a face-plate 12, and clamping-arms 13, said plates and clamping-arms being similar to the corresponding parts of the upper clamping member, with the exception
15 that the approximate faces of the plates are plane. The face-plate 12 of the lower clamping member is provided near each end and in alinement with the lower edge with a lug or stop 14, preferably in the form of an elongated
20 strip secured to the outer side of the plate 12 in a manner to provide an offset from the plane of said plate. These stops are arranged to underlie and contact with the free terminals of the clamp-arms 13 when the latter are in clamping position, thereby preventing an independent upward movement of the plate 12 when the trousers are positioned in the stretcher, it being obvious that the strain incident to the use of the stretcher tends to
25
30 draw the face-plate upward, which movement is effectually prevented by the use of the stop referred to.

The brace member, which is designed to force the respective clamping members apart when the stretcher is in use, comprises a tubular section 15 and a rod-section 16, arranged to telescope within the tubular section. The rod-section is provided for the greater portion of its length with a series of transversely-arranged openings 17, designed to receive a key 18, which is inserted through a longitudinal slot 19, formed in the tubular section 15 near the upper end of the latter. The slot 19 is of sufficient length to permit the desired movements of the parts during the stretching operation, and, if preferred, the rod-section may be graduated in inches or the like to provide for the proper initial adjustment of the parts, as hereinafter described. A short length of the material of the tubular section 15, cut away and providing the slot 19, is left integral with said section and bent outwardly therefrom to provide a lug 20 at the upper end of the slot 19.

55 The tension medium of the stretcher comprises a coiled spring 21 of a size to snugly encircle the tubular section of the brace member. The upper end of the spring is connected to a clamp-bar 22, formed with a transverse opening 23, slightly greater in diameter than the diameter of the rod-section 16. When assembled, the clamping-bar is arranged at right angles to the length of the rod-section, being slidably connected therewith through the medium of the opening 23, said

60

65

clamping-bar being of a length to extend a short distance in each direction from said rod-section. The upper terminal of the coiled spring is secured to one end of the clamping-bar by any suitable connection, the opposite 70 end of said bar being suitably formed to provide a finger-grip 24.

The brace member is adapted for removable connection with respect to the clamp members through the medium of connecting-plates 25, secured, respectively, to the upper end of the rod-section and to the lower end of the tubular section. Each of these plates comprises a horizontal portion 26, centrally of which the respective ends of the rod-section and tubular section are secured, the horizontal portion of the plate being of sufficient dimensions to project radially beyond the surface of the respective sections of the brace member to provide a broad bearing-surface for the clamping members. The remaining portion of the plate comprises a spring-section 27, extending approximately parallel with the respective sections of the brace member, but slightly offset therefrom, the free ends of said sections 27 being flared or turned outwardly away from the section of the brace member to which they are connected. Studs 28 project vertically and centrally from the horizontal portion 26 of the plate, said studs extending in longitudinal alignment with the sections of the brace member, as clearly shown in Fig. 2. The brace member at the upper end is connected to the upper clamping member through the engagement of the stud 28 with an opening 29, formed in the lower end of the swiveled block 9, the spring-section 27 of the plate at this point bearing against the face or outer surface of the swiveled block and engaging a pin 30, projecting from the face of the block, an opening 31 being formed in the spring-section for the reception of the pin 30. The plate provided at the lower end of the tubular section 15 is arranged for similar engagement with the base-plate of the lower clamping member, and an opening 32 being provided centrally of said base-plate for the reception of the stud 28, the spring-section 27 of the plate bearing on the outer surface of the base-plate and having an opening 33 to engage a pin 34, carried by the base-plate.

* By the construction described it will be noted that the brace member is fixedly connected to the lower clamping member, so that any independent movement of the latter is prevented, while the upper clamping member is movably connected to the brace member through the medium of the swiveled block 9. 120

In operation, assuming the parts constructed and arranged as described, the respective sections of the brace member are initially adjusted through the medium of the key 18 and the openings in the rod-section to separate the clamping members a distance approximately 130.

proximately equal to the length of the trousers to be stretched. The lower ends of the trousers are inserted in the upper clamping member, being placed upon the base-plate, 5 and the face-plate of said member placed in position as described and the clamping-arms 7 turned to secure the trousers at this point. The upper or waist end of the trousers are similarly inserted in the lower clamping member, 10 the trousers being slightly stretched during this operation to cause a telescoping action of the rod-section 16 within the tubular section 15, this movement of the parts being limited by the contact of the key 18 with the 15 lower wall of the slot 19. The clamping-bar 22 is now manually adjusted longitudinally 20 of the rod-section 16 and released, the tension exerted by the spring upon one end of the bar causing the bar to tilt, and thereby bind itself 25 upon the rod 16, practically locking the bar to the rod. As the spring is thereby held under tension, bearing at one end against the lug 20, carried by the tubular section, and at the other end against the clamping-bar practically locked to the rod, the clamping members are forced apart to the limit of the material fixed in the stretcher.

It is obvious that the spring 21 may be readily and conveniently adjusted to place 30 the garment under any desired tension and that said adjustment is not limited by the arrangement of notches or similar holding means heretofore common in devices of this character. The respective movements of the 35 rod-section and tubular section under the effect of the spring are limited solely by the length of the slot 19, and this slot is designed and intended to be of sufficient length to provide the maximum movement necessary.

40 It will be further noted that the lower clamping member is rigidly connected with the brace member, but that the upper clamping member is movably connected therewith through the medium of the swiveled bar 9. 45 The movable connection between the brace member and clamping member is, in effect, a pivotal connection so arranged as to permit an independent swinging movement of the clamping member in the longitudinal plane 50 of the brace member. This feature of construction is important in that it provides for a proper adjustment of the garment within the stretcher notwithstanding the possibility of placing the lower ends of the trousers improperly in the upper clamping member—that is, not exactly at right angles thereto—as in this event the manual stretching effected in placing the upper end of the trousers in the lower clamping member will swing the upper 55 clamping member on its pivotal connection with the block 9, and thereby insure the proper position of the trousers between the clamping members, so that the stretching operation will be properly carried out.

60 65 When not desired for use, my improved

garment-stretcher may be disconnected by separating the connecting-plates from the respective clamping members in an obvious manner and turning the swiveled block 9 in alinement with the length of the clamping- 7c plates. The rod-section 16 is wholly telescoped within the tubular section of the brace member by removing the key 18, the coiled spring 21 being moved downward until the clamping-bar 22 rests upon the upper end of the tubular section 15. This movement of the 75 spring is accomplished by a revolution thereof about the tubular member, causing the lug 20 to ride between the successive coils of spring and feed the same downward upon the 80 tubular member. In this condition of the parts three separate members are provided of comparatively the same length and of small compass, thereby affording a convenient package for storage or transportation. 85

While I prefer that the clamping members be constructed of wood, it is obvious that they may be made of metal or similar material and that the particular proportions shown and described may be varied to suit a particular garment or size of garment. 90

It is equally obvious that while shown and described primarily for use as a trousers-stretcher my improved device is also serviceable for stretching other garments, such as 95 skirts and the like.

Having thus described the invention, what is claimed as new is—

1. A garment-stretcher comprising clamping members for the respective ends of the 100 garment, and a brace member connecting said clamping members, said brace member being pivotally connected to one clamping member and fixedly connected to the other clamping member, said pivotal connection 105 providing for movement of said member in the longitudinal plane of the connected member.

2. A garment-stretcher comprising clamping members for the respective ends of a garment, and a brace member connecting said clamping members, one of said members being pivotally mounted with relation to the brace member, and the other of said members being fixed with relation thereto, said pivotal 110 connection providing for movement of said member in the longitudinal plane of the connected member. 115

3. A garment-stretcher comprising clamping members for the respective ends of the 120 garment, and a brace member connecting said clamping members, said brace member comprising a tubular section and a rod-section, the tubular section being fixed with relation to one clamping member and the rod-section 125 pivotally connected to the other clamping member, said pivotal connection providing for movement of said member in the longitudinal plane of the connected member.

4. A garment-stretcher comprising clamp- 130

ing members, and a brace member connecting said clamping members, said brace member comprising a tubular section, a rod-section 5 slidably mounted therein, means for limiting the movement of the rod member with relation to the tubular section, and a spring encircling said sections and bearing at one end against the tubular section, the opposite end of the spring being adjustably connected to the rod-section.

5. A garment-stretcher comprising clamping members, and a brace member connecting said clamping members, said brace member comprising a tubular section and a telescoping rod-section, means for limiting the telescoping movement of the rod-section in both directions, and a spring bearing at one end against the tubular section and secured at the opposite end to a clamping-bar adjustable longitudinally of the rod-section.

6. A garment-stretcher comprising clamping members, and a brace member connecting said clamping members, said brace member comprising a tubular section and a rod-section 25 slidably mounted therein, the tubular section being formed with a longitudinal slot and the rod-section with a series of transverse openings, a key projecting through said slot and engaging one of the openings in the

rod-section, a spring encircling the sections 30 and bearing at its lower end against the tubular section, a clamping-bar slidably engaging the rod-section, the upper end of the spring being connected to said bar beyond the plane of the rod, whereby the tension of 35 said spring when adjusted will clamp the bar to the rod.

7. A clamping member for garment-stretchers comprising a base-plate, lips projecting at right angles from said base-plate, a 40 face-plate designed for contact with the base-plate and provided with loops to receive said lips, and clamping-arms pivotally connected with the base-plate and designed to bear upon the outer surface of the face-plate.

8. A garment-stretcher comprising clamping members, a brace member connecting said clamping members, locking-plates carried by the respective ends of the brace member to engage the clamping members, one of 50 said locking-plates engaging a block swiveled to one of the clamping members.

In testimony whereof I affix my signature in presence of two witnesses

TUDOR T. HALL.
